LUM WOODRUFF, OF ANN ARBOR, MICHIGAN.

Letters Patent No. 61,594, dated January 29, 1867.

IMPROVED GATE LATCH.

The Schedule referred to in these Letters Patent and making part of the same.

TO ALL WHOM IT MAY CONCERN:

Be it known that I, LUM WOODRUFF, of Ann Arbor, in the county of Washtenaw, and State of Michigan, have invented a new and useful improvement in Gate Fastenings; and I do hereby declare that the following is a full and exact description thereof, reference being had to the accompanying drawings, and to the letters of reference marked thereon.

It is the object of this improvement to furnish a fastening which shall give support to the gate when closed so that it cannot sag, which shall be secure against the accidental disturbances of animals, winds, &c., and which admits the gate to swing either way in opening, the device being at the same time simple and easily operated by the hand.

In order to effect these results I fix firmly in the outer stile of the gate an iron pin, A, from one to two inches in length and three-quarters of an inch in diameter. The rest B and the slotted latch C are so placed with reference to this pin, that as the gate is closed from either side the pin passes between the two pieces, rising slightly, (say one-eighth of an inch,) on the rest B, and pressing up the latch C until it comes under the slot a, when the latch returns to its place and the gate is securely fastened. The latch C is held in its proper position by means of the projecting tongue D, Figure 2, which plays readily in the slot E, Figure 3. It is further steadied by the rod F which passes through the guide b. To facilitate the easy opening of the gate, the rod F rises to the level of the top of the gate and is bent in the form of a loop, c, large enough to admit the hand. Over this loop and concentric to it is placed the stationary handle d. By grasping the two loops at once in the hand, the latch-rod F is easily drawn up and the pin released from the latch. The latch returns to its place by its own weight, or if that is not sufficient a helical spring may be added, as shown at e, fig. 2.

What I claim as my invention, and desire to secure by Letters Patent, is—

I claim the pin A, the rest B, the slotted latch C, and the vertical looped rod F, when arranged substantially in the manner and for the purposes above specified.

LUM WOODRUFF.
